UNITED STATES PATENT OFFICE.

CHARLES W. STEVENS, OF HARVEY, ILLINOIS.

MANUFACTURE OF ARTIFICIAL STONE.

SPECIFICATION forming part of Letters Patent No. 722,464, dated March 10, 1903.

Application filed April 6, 1901. Renewed January 2, 1903. Serial No. 137,572. (No model.)

To all whom it may concern:

Be it known that I, CHARLES W. STEVENS, of Harvey, in the county of Cook, State of Illinois, have invented certain new and useful Improvements in the Manufacture of Artificial Stone, of which the following is a complete specification, reference being had to the accompanying drawing.

The object of my invention is to produce an improved method of manufacturing certain articles—such as sewer-pipes, conduits, and the like—from artificial stone, whereby the stone may be made of uniform density throughout.

My invention is adapted for the manufacture of articles from artificial stone generally; but in the manufacture particularly of sewer-pipes from artificial stone difficulty has been experienced in insuring against the presence of air-bubbles. Consequently in the manufacture of such articles as a general practice the stone material is tamped or driven into a mold. By my invention I obviate the necessity of tamping and am enabled to make the article successfully by pouring the mixture into the mold and at the same time to insure results equal to those obtained by the more expensive and tedious processes. Moreover, in the manufacture of such articles by processes in which tamping is employed there is difficulty experienced in securing uniformity of density, an objection obviated by my process.

In the accompanying drawing I illustrate a central vertical section of one form of apparatus adapted to carry out my process in the manufacture of sewer-pipes.

Referring to the numerals on the drawing, 1 indicates the case or outer shell of a mold provided with a closed bottom 2, attached thereto.

3 indicates a core, which may be made of any suitable material, extending from the bottom and defining between it and the shell the mold-cavity, which in the form illustrated is adapted to mold a section of sewer-pipe.

4 indicates a ring which, surrounding the lower end of the core 3, is adapted to form the joint-flange on the pipe.

5 The case 1 is closed by a removable lid 5, which may be provided with a rubber or other gasket 6 for forming an air-tight joint

between the lid and the case. In the upper part of the case 1 I provide an annular tray 7, having a foraminous or perforated bottom 55 8. The tray fits the upper end of the mold-cavity and is adapted to support therein a layer of porous or permeable material, preferably sand.

9 indicates a supply-pipe which, entering the mold-cavity below the tray, is adapted to supply by an air-tight connection a stone mixture in a liquid state to the interior of the mold. This stone mixture may be of any preferred kind, consisting, for example, of cement, sand, slag, or ground stone, with sufficient water to render it fluid and with any coloring-matter or other material which may be desired.

10 indicates an air-exhaust pipe which 70 communicates with the mold-cavity, preferably above the tray, and being connected with air-pumping mechanism on the outside of the case is adapted to produce a partial vacuum within the mold-cavity. The pipe 75 10 may also be employed to carry off with the air such superfluous water as may accumulate above the tray, the tray acting as a strainer for the separation of the water from the solid particles contained therein.

In carrying out my process the parts being properly assembled and the lid 5 being closed and secured against its gasket 6 the air is preferably first exhausted from the mold. Then afterward the stone mixture is supplied 85 to the mold through the pipe 9, the air being kept pumped out while the mold is being filled. The pumping out of the air ahead of the incoming stone mixture insures the proper filling of the mold and the absence of air-bubbles. This in itself tends to render the stone formed in the mold of uniform density; but in addition to that provision is made in the presence of the tray with its porous contents for securing the same result, the operation 95 being as follows: As the mold-cavity fills with the stone mixture its level within the cavity rises until it reaches the foraminous bottom of the tray, when the porous contents of the tray permit the passage through it of 100 the superfluous water in the stone mixture, but retains its solid constituents within the cavity. In other words, the porous contents of the tray act as a strainer, so that the mold-

cavity will be completely and uniformly filled with the stone mixture of equal density, the water which holds the mixture in solution passing off through the tray, and thence 5 through the pipe 10.

For some purposes the case 1 or the core 3, or both, might be made of or lined with sand, in which event it would be sufficient to employ means for pumping out the air ahead of 10 the supply of stone mixture without employing the strainer, although the strainer might still be used, if desired. For other purposes the strainer might be employed advantageously without pumping out the air. It 15 would therefore appear that while my process contemplates the simultaneous exhaust of air and the forcing of the mixture against a strainer, yet it is obvious that those two features of my present invention may be employed independently to advantage under certain 20 circumstances.

What I claim is—

1. An improvement in the manufacture of

artificial stone, which consists in forcing a stone mixture in a liquid state into a closed 25 mold provided with a permeable wall, whereby the liquid portion of the mixture is forced out of the mold through the permeable wall by pressure derived by accretion to the solid portion of the mixture.

2. An improvement in the manufacture of artificial stone, which consists in forcing a stone mixture in a liquid state into a closed 30 mold provided with a permeable wall, whereby the liquid portion of the mixture is forced out through the permeable wall, by pressure derived by accretion to the solid portion of the mixture, the body of said mixture being contained within a partial vacuum.

In testimony of all which I have hereunto 40 subscribed my name.

CHARLES W. STEVENS.
